His Attorney.

UNITED STATES PATENT OFFICE.

GUSTAV PAGEL, OF CHARLOTTENBURG, GERMANY, ASSIGNOR TO GENERAL ELECTRIC COMPANY, A CORPORATION OF NEW YORK.

CENTRIFUGAL PUMPING APPARATUS.

1,246,149.

Specification of Letters Patent.

Patented Nov. 13, 1917.

Application filed October 8, 1915. Serial No. 54,750.

To all whom it may concern:

Be it known that I, GUSTAV PAGEL, a subject of the King of Prussia, residing at Charlottenburg, Germany, have invented 5 certain new and useful Improvements in Centrifugal Pumping Apparatus, of which the following is a specification.

The present invention relates to centrifugal pumping apparatus of the type comprising 10 a combined liquid pump and gas and vapor pump, and particularly to such apparatus for removing the water of condensation and the air, vapor, and uncondensed gases from condensers.

15 In the following specification I have described my invention as applied to such use but it is to be understood that it is not necessarily limited thereto. The object of the invention is to provide an improved 20 structural arrangement for an apparatus of this type.

For a consideration of what I believe to be novel and my invention, attention is directed to the accompanying specification and 25 the claims appended hereto.

In the accompanying drawing, Figure 1 is a sectional view of an apparatus embodying my invention, and Fig. 2 is a section at right angles to Fig. 1, the section being 30 taken on line 2—2 of such figure.

Referring to the drawing, 3 indicates a driven shaft which will be suitably supported in a bearing in any approved manner and which projects through a stuffing box 4 in 35 the casing of the pumping apparatus. The pumping apparatus comprises essentially two pumps, a condensate pump and an air and vapor pump of the water throwing type. 5 indicates the impeller of the water pump 40 and 6 the impeller of the air pump. They are mounted in spaced relation on the end of the shaft 3 which may be driven by any suitable motor. The casing for the water pump comprises an annular portion 7 in 45 which stuffing box 4 is arranged and which houses the impeller 5 and the discharge scroll 8 which surrounds the impeller 5 and terminates in a discharge opening in the usual manner. This discharge opening does 50 not show in either of the views of the drawing. 9 indicates the admission conduit which is common to both the water and air pumps, and 10 indicates the suction chamber of the water pump from which water passes

through the admission openings 11 of the 55 impeller to the vanes 12. The suction chamber 10 is formed by a wall or partition 13 which surrounds the shaft and the eye of the impeller and defines an admission opening 14 at the bottom of the chamber and the 60 two passages 15 and 16 through which the water to be pumped flows to the suction chamber. The object of this arrangement is to provide a liquid seal or trap for the water pump to prevent air from being sucked into 65 the impeller 5 at times when the supply of water to the impeller is limited. It will be clear that were this partition not present, when the supply of water for the pump was less than the total capacity of the chamber, 70 that the upper portion of the inlet of the impeller would receive no water. This would mean that it would suck in air which is often objectionable, as for example, where the condensate is being used as feed water for boilers.

This is because the presence of air in the water may cause corrosion of the boiler wall. The partition 13 projects down so far that air cannot enter the admission opening 14 even at the lowest level of the water 80 on the suction side of the pump. 18 indicates a wall or dam in the admission conduit 9 which defines a passage 19 for conducting air and vapor to the air pump, here specifically illustrated as an air pump of the 85 water throwing type and also prevents water from entering the air pump. The paths of the water and air in passing to their respective impellers are indicated by the arrows in Fig. 2. 20 indicates the throwing water 90 inlet through which throwing water is led to the impeller 6. Surrounding the impeller 6 is an annular discharge ring or member 21, there being an annular space or passage as indicated at 22 between them. The air, 95 vapor and other gases flow from the passage 19 to the annular chamber 23 at the side of the impeller 6 which chamber communicates with the space 22. The discharge ring 21 is provided with suitable directing vanes 24 100 forming between them suitable discharge passages which communicate at their outer ends with the discharge scroll 25. The discharge opening or conduit for the air pump is indicated at 26. The impeller 6 is provided with suitable vanes 27 in the usual manner.

As already stated, it is desirable to pre-

vent air from being pumped along with the condensate, and in order to prevent leakage around the shaft 3 from the annular space 28 to the suction chamber 10 of the water pump, I have provided an improved form 5 of packing which constitutes the principal feature of my invention. Preferably formed integral with the intermediate wall 28 which forms a part of the casing of the 10 pumps I provide a hub 28^a between the inner surface of which and the shaft are provided serrations to form a packing of the labyrinth type. These serrations may be formed on either the shaft or on the 15 inner surface of the hub, the latter arrangement being shown in the present instance. I then provide a liquid seal for this packing which comprises a wall 29 shaped to form a cup or reservoir 30. 31 is a passage 20 which connects this cup or reservoir with the packing. Formed integral with the inlet conduit 9 is a projecting ledge 32 which directs the water entering by way of conduit 9 into the reservoir 30, the excess 25 spilling over the edge of the same and passing through the passages 15 and 16 to the suction chamber of the water pump. Water from the reservoir 30 runs down through passage 31 to the packing to seal it. By 30 this arrangement it will be seen that I utilize the water of condensation which is very readily available and which is the medium being pumped, as my sealing liquid, and that so long as there is any water 35 being pumped there will always be a supply for sealing the packing. Furthermore, this water which flows through the packing escapes directly to the suction side of the pump so that it is not lost and is available 40 for feed water. The arrangement thus avoids the necessity of providing a separate liquid under pressure for sealing purposes, and avoids any losses of the liquid used for packing. In some instances it may be desirable 45 to prevent air from entering the suction chamber 10 of the condensate pump by way of passage 31 and thence through the packing, when the pump is standing idle and to this end a suitable float controlled valve may be provided which is controlled 50 by the level of the liquid in the reservoir 30, and which closes the passage 31 when all or substantially all of the liquid has run out of the reservoir. By way of 55 example I have illustrated a valve 33 which floats on the liquid and acts to close the passage 31 when the level therein reaches a predetermined low point.

In operation the condensate, and the air, 60 vapor, and other gases from the condenser pass through the conduit 9 and the condensate is directed by the wall 18 and lip 32 into the reservoir 30, a portion of it passing from there through passage 31 to seal the 65 packing and the excess spilling over the

edge of the cup and running through passages 15 and 16 to the suction chamber 10 from which it passes to the impeller and is pumped out, as is well understood. The air, vapor, and other gases enter through 70 the passage 19 to the chamber 23 of the air pump. The throwing water enters the impeller 6 through the inlet 20 and is discharged across the gap or annular space 22 entraining air and other gases in its passage 75 from the chamber 23 in the well understood manner. The throwing water and entraining air and gases are discharged by way of the scroll 25 and discharge conduit 26. 80

In accordance with the provisions of the patent statutes, I have described the principle of operation of my invention, together with the apparatus which I now consider to represent the best embodiment thereof; 85 but I desire to have it understood that the apparatus shown is only illustrative and that the invention can be carried out by other means.

What I claim as new and desire to secure 90 by Letters Patent of the United States is:—

1. In combination, a combined liquid and gas pump having an intermediate wall in common, a shaft passing through it, a packing for the shaft, means forming a liquid 95 seal for said packing, and means forming a trap on the suction side of the liquid pump which is filled with liquid being pumped to also form a liquid seal, said liquid seals acting to prevent gaseous material from being sucked into the liquid pump.

2. In combination a combined liquid pump and gas pump having an intermediate wall in common and a shaft passing 105 through it which carries the impellers for the pumps, a packing for the shaft where it passes through the wall, means for supplying liquid being pumped to said packing to form a seal for it, and means forming a trap on the suction side of the liquid pump which is filled with liquid being pumped to also form a liquid seal, said liquid seals acting to prevent gaseous material from being sucked into the liquid 110 pump.

3. A combined liquid and gas pump comprising a casing, a shaft, impellers mounted on the shaft in spaced relation, a wall dividing the region between the impellers into 120 two chambers, a partition in one of the chambers which surrounds the eye of the impeller for the liquid pump and has an opening at its lowest point, a packing for the shaft where it passes through said wall, and means for supplying liquid being pumped to said packing to seal it. 125

4. The combination of a casing having an inlet, an impeller therein, a shaft for the impeller, a partition member in the casing 130

which surrounds the eye of the impeller and has an opening at its lowest point for admitting liquid to the impeller, said partition member defining a passage for conveying liquid to the opening, a packing for the shaft, and means for supplying liquid being pumped to the packing to seal it.

5. The combination of a casing having an inlet, an impeller therein, a shaft for the 10 impeller, a partition member in the casing which surrounds the eye of the impeller and has an opening at its lowest point for admitting liquid to the impeller, said partition member defining a passage for conveying 15 liquid to the opening, a packing for the shaft, a reservoir in the inlet above the packing into which liquid being pumped is directed, and means forming a passage connecting said reservoir to the packing to form 20 a liquid seal therefor.

6. In a combined liquid pump and gas pump of the water throwing type, comprising a shaft with spaced impellers thereon, and a partition wall between the impellers 25 which defines two chambers one for the liquid pump and the other for the gas pump, of a packing for the shaft where it passes through the partition, and means for directing liquid being pumped to said packing to seal it so as to prevent gases from leaking around the shaft from one chamber to the other.

7. In a combined liquid pump and gas pump of the water throwing type, comprising a shaft with spaced impellers thereon, and a partition wall between the impellers which defines two chambers one for the liquid pump and the other for the gas pump, of a packing for the shaft where it 35 passes through the partition, a reservoir above the packing to which liquid being pumped is supplied, and means forming a

passage connecting the reservoir to the packing to form a seal for it.

8. In a combined liquid pump and gas 45 pump of the water throwing type, comprising a casing, an inlet thereto, a shaft with spaced impellers thereon, and a partition wall between the impellers which defines two chambers one for the liquid pump and 50 the other for the gas pump, of a packing for the shaft where it passes through the partition, a reservoir in the inlet above the packing, means directing the liquid being pumped to said reservoir, the excess of 55 liquid overflowing the edge of said reservoir and flowing to the liquid pump, and means forming a passage connecting the reservoir to the packing to form a seal for it.

9. In a combined liquid pump and gas 60 pump of the water throwing type, comprising a casing, an inlet thereto, a shaft with spaced impellers thereon, and a partition wall between the impellers which defines two chambers one for the liquid pump and 65 the other for the gas pump and with which chambers said inlet communicates, of means in said inlet for directing the liquid to the liquid pump and the gases to the gas pump, a partition member in the chamber for the 70 liquid pump which surrounds the eye of the impeller and has an opening at its lowest point through which liquid is fed to such impeller, a packing for the shaft where it passes through the partition, a reservoir 75 above the packing to which the liquid being pumped is supplied, and means forming a passage connecting the reservoir to the packing to form a seal for it so as to prevent gases from leaking around the shaft from 80 one chamber to the other.

In witness whereof, I have hereunto set my hand this 6 day of September, 1915.

GUSTAV PAGEL.
